UNITED STATES PATENT OFFICE.

JOHN C. SHIGLEY, OF MAXBASS, NORTH DAKOTA.

HEN'S NEST.

1,210,550.

Specification of Letters Patent. Patented Jan. 2, 1917.

Application filed July 17, 1916. Serial No. 109,705.

To all whom it may concern:

Be it known that I, JOHN C. SHIGLEY, a citizen of the United States, residing at Maxbass, in the county of Bottineau and State of North Dakota, have invented certain new and useful Improvements in Hens' Nests; and I do declare the following to be a full, clear, and exact description of the invention, such as will enable others skilled in the art to which it appertains to make and use the same.

This invention relates to new and useful improvements in hens' nests, and the primary object of the invention is to provide a novel arrangement for suspending a hen's nest in a casing wherein as the hen occupies the nest the opening through which she enters the casing will be automatically closed, and the hen will not be disturbed while occupying the nest.

Another object of the invention is to provide a device of this character which is adapted to act as a trap nest, whereby a hen, upon occupying a nest will automatically close and lock the entrance through the casing, and will be thereby imprisoned in the same.

A further object of the invention is to provide a device of this character which is easily and simply constructed, inexpensive to manufacture, and one which will be very efficient in operation.

With these and numerous other objects in view, my invention consists of the novel features of construction, combination and arrangement of parts which will be herein referred to and more particularly pointed out in the specification and claimed.

Figure 1 is a substantially vertical longitudinal section of my improved hen's nest; Fig. 2 is a plan view of the same with the top removed; Fig. 3 is an elevation of the front of the nest; Fig. 4 is an elevation of the rear end of the same; and Fig. 5 is a vertical section of a portion of the rear end of the trap taken on the line 5—5 of Fig. 4.

In describing my invention I shall refer to the drawings in which similar reference characters indicate corresponding parts throughout the several views and in which the numeral 1 designates a substantially rectangular shaped casing having in the front end 2 of the same an opening 3, disposed adjacent its bottom, and at one side thereof.

Positioned within the casing 1 is a hinged

pan 4, which is adapted to receive the nest 5, which the hen occupies when in the device. This pan 4 is mounted on a hinged bar 6, which extends transversely between the sides of the casing 1, and the same is secured thereto at its forward end as shown at 7. The bottom of the casing is open a short distance below the forward end of the hinged pan 4, so that the same may swing freely within the casing without any possibility of binding against its bottom.

The pan 4 is normally held in elevated position by means of a coil spring 8, which has its lower end 9 secured to the free or rear end of the pan, and the upper end 10 of the coil spring secured to the lower end of the screw bolt 11 that projects downwardly from the top of the casing, and is vertically adjustable by means of a thumb nut 12 which is secured to its upper end above the top of the casing. By this means the tension of the coil spring may be adjusted to accord with the weights of different varieties of hens.

Positioned in a longitudinally extending groove 13 in the bottom of the casing is a rock shaft 14, which has projecting laterally and upwardly from the rear end of the same a crank 15, which projects up through an opening in the bottom of the casing, and has its extremity fastened to the bottom of the hinged pan 4, adjacent the rear end of the same. Any type of connecting means between the extremity of the crank 15, and the bottom of the pan may be used, preferably the type illustrated in the accompanying drawings.

The front end of the rock shaft 14 projects out past the front of the casing, and has formed thereon an upwardly projecting upright arm 16 which is bent adjacent its free end as shown at 17, and has loosely mounted on said bent portion a swinging door or closure 18. This door or closure 18 is mounted on the arm adjacent its top, and the same is provided with a plurality of openings 19 therethrough, for the purpose of allowing a light to enter the casing, when this door is disposed over the outlet of the same.

The projecting free end of the arm 16 which is designated by the numeral 20, extends upwardly to a point adjacent the top of the casing, and is positioned in one end of a guide 21 that is formed by a wire spaced from the front of the casing, and ex-

tending arcuately, downwardly and laterally therefrom. The door 18 is also provided with a guide which comprises a wire 22 bent intermediate its ends as shown at 23, and having two portions formed thereby disposed in different horizontal planes, the portion 24 being disposed adjacent the door when the same is open and the portion 25 being disposed adjacent said door when the same is closed. The ends of the wire 22 are secured in the front of the casing, and the wire is spaced a sufficient distance therefrom to allow the door to swing freely between the same and the said front.

From the above described construction it will be obvious that through the action of the coil spring 8 the hinged pan 4 in which the nest is disposed, will be normally held with its rear end elevated, so that the crank 15 will be lifted, and hence the arm 16 will be in upright position as clearly shown in Fig. 3 of the drawings, whereby the door 18 will be normally held at one side of and a little above the opening 3 through the front of the casing. Upon a hen entering the casing through said opening and occupying the nest, the hinged pan will be depressed against the tension of the spring 8, whereby the crank 15 will be moved downwardly, and the shaft 14 rocked which will cause the arm 16 to swing laterally and downwardly, and the swinging door 18 being secured thereto will swing over the outlet 3 thus keeping the hen in the casing. The swinging door 18 is mounted in such a manner upon the bent portion of the arm 16, that the same will always be held upright although the arm 16 swings in an arc. The extremity of the arm 16 will be guided by the guide 21, while the downward and sideward movement of the door 18 will likewise be guided by the guiding means 22 provided for the same. Upon the hen leaving the nest the coil spring will again elevate the pan 4 and consequently upon the rocking of the shaft 14 the door will be swung back to its original position. The rear end 26 of the casing is provided with elongated opening 27 therethrough, which is disposed adjacent the swinging free end of the pan 4, so that when the pan 4 is in elevated position the inner end of this opening will be closed, but when the pan is depressed the opening will be free. Disposed alongside of the opening 27 is a depression 28 the purpose to be hereinafter more fully described.

Mounted above the opening 27, and on the outer surface of the rear end 26 of the casing is a latch member 29, which comprises a horizontal portion 30 hingedly and slidably mounted with respect to the rear end of the casing in bearings 31, and having one of its ends bent laterally as shown at 32 and provided with a depending handle 33 on its extremity. The other end of the horizontal

tally extending portion 30 is formed with a depending portion 34, that has its extremity bent laterally and inwardly as shown at 35 and disposed normally in alignment with the opening 27. In operation this latch is so positioned that the end 35 will be normally held in the opening 27, and upon the depression of the hinged pan 4, when this opening will be clear, this portion of the latch will project through the rear end of the casing, and will be disposed above the free edge of the pan, and hence will prevent the pan from returning to elevated position. This swinging movement of the latch member is brought about owing to the fact that the depending handle 33 will overbalance the same and cause its forward movement. When in this position it will be obvious that when the hen leaves the nest, the same will not return to its elevated position, and hence the opening in the front end of the casing will remain closed and the hen will be entrapped in the casing. The upward movement of the handle 33 will release the hinged pan 4, and if the hen does not still occupy the nest, the same will swing upwardly and open the outlet in the casing. When it is, however, not desired to use this automatic latch, the horizontal portion of the latch member is moved longitudinally, until the portion 35 of the member will be disposed within the depression 28 in the end of the casing, whereby the nest will act automatically as was first described.

From the foregoing description of the construction and operation of my improved hen's nest, the manner of applying the same to use with the operation thereof will be easily understood, and it will be seen that I provide a simple and efficient means for carrying out the objects of this invention. The swinging door 18 used as a closure for the front of the casing is perforated, so that when the hen desires to leave the nest, she will be attracted by the light filtering through the door and hence will move forwardly to release the operating means whereby the door is swung from over the opening to allow the hen to leave the casing.

I claim:

1. A hen's nest comprising a casing having an opening in its front, a tilting pan with one end normally elevated disposed in said casing, a rock shaft disposed beneath said casing, a crank on the rear end of said shaft engaging the elevated end of said pan, an arm on the front end of the shaft disposed across the front of the casing, a door loosely mounted on said arm and adapted to swing laterally and downwardly to close the opening in the casing upon depression of said pan, and guiding means for said door and arm.

2. A hen's nest comprising a casing having an opening in its front, a tilting pan

with one end normally elevated disposed in said casing, a rock shaft disposed beneath said casing, a crank on the rear end of said shaft, an upright arm on the front end of said shaft disposed across the front of the casing, said arm being bent laterally adjacent its free end, a door loosely mounted on said bent portion and adapted to maintain an upright position upon movement of the 10 arm, an arcuate guide for the free end of said arm spaced from the front of the casing, and a spaced guide for the swinging door disposed in different horizontal planes for disposition across the front of said door 15 when the same is opened or closed.

3. A hen's nest comprising a casing having an opening in its front, a pan pivotally mounted in said casing and adapted to swing vertically, a rock shaft in the bottom 20 of the casing, a crank at the rear end of said shaft operatively connected with the pan, an arm on the front end of the shaft disposed across said front of the casing, a door loosely pivoted on said arm and adapted 25 to swing laterally and downwardly to close the opening in the casing, a guide for said arm and door, and a spring connected with said pan to hold the same normally elevated whereby the door will be held in 30 open position.

4. A hen's nest comprising a casing, means to automatically open and close an opening in the same by the elevation or depression of a normally elevated hinged pan having its free end disposed adjacent the 35 rear of the casing, said end of the casing having an opening therethrough normally closed by the elevated pan but opened upon the depression of the same, a latch including a horizontal portion slidably and hingedly mounted on said rear end having a lateral offset at one end with a handle depending therefrom, a downwardly bent portion at the opposite end of the latch member with a laterally bent extremity positioned in the opening in said casing and adapted to project therethrough to lock the pan when the same is depressed, and said extremity being movable out of alignment with the opening upon sliding movement of the horizontal portion of the latch member. 40 45 50

In testimony whereof I have hereunto set my hand in presence of two subscribing witnesses.

JOHN C. SHIGLEY.
